WALL BOARD

Original Filed June 9, 1925 2 Sheets-Sheet 2

INVENTOR:
EDWARD J. O'BRIEN,
BY
Ed W. O'Brien
ATTORNEY.

UNITED STATES PATENT OFFICE.

EDWARD J. O'BRIEN, OF MONTROSE, CALIFORNIA, ASSIGNOR, BY MEANS ASSIGNMENT,
TO CLAUS T. HODNETFIELD, OF MONTROSE, CALIFORNIA.

WALL BOARD.

Application filed June 9, 1925, Serial No. 35,885. Renewed June 5, 1928.

My invention relates to wall constructions, and particularly to a novel form of wall board adapted for use in such constructions.

It is common practice in the building industry to form walls of vertical studs to which laths are nailed. The laths are placed a short distance apart to provide small spaces therebetween. The laths are covered with plaster which completes the wall. The plaster enters the spaces between the laths and is thus keyed thereto. Wall board has come into general use because it is cheaper than lath. Wall board consists of a layer of plaster interposed of two layers of paper. Wall board has one marked disadvantage, however. After plaster has been applied to a surface, moisture of the plaster is absorbed by the wall board, which absorption results in an expanding and buckling of the wall board. The finished wall is therefore irregular and such buckling sometimes results in a subsequent cracking of the wall.

It is an object of my invention to provide a wall board which may expand without buckling.

It is another object of my invention to provide a wall board having novel means which permit an internal expansion, thus eliminating any buckling.

It is a still further object of my invention to provide a wall board having keys for plaster. The wall board is so designed that the plaster will be keyed thereto, but there will be saved approximately 40% of plaster in comparison with the plaster required on ordinary laths.

It is a still further object of my invention to provide wall board having a novel form of end member which prevents splitting when the wall board is secured in place.

Other objects and advantages of this invention will be made evident hereinafter.

Referring to the drawings in which I illustrate my invention:

Fig. 1 is a face view of a sheet of a wall board of my invention.

Fig. 2 is a fragmentary view of my invention, lacing members being installed on the sheet shown in Fig. 1.

Fig. 3 is a section taken on the line 3—3 of Fig. 2 clearly showing the means of my invention for permitting expansion of the sheet without buckling.

Fig. 4 is a section taken on the line 4—4 of Fig. 2, clearly showing the manner of bending strips of the sheet shown in Fig. 1.

Fig. 5 is a view similar to Fig. 3, but showing the wall board after plaster has been applied thereto and after it has expanded.

Fig. 6 is a section taken on the line 6—6, clearly showing the end member of my invention.

Fig. 7 is a face view of the wall board shown in Fig. 2 expanded by moisture.

With particular reference to Fig. 1, my invention provides a sheet 11 which is preferably made from a thin layer of wood or in some cases may be made of cardboard or metal. The sheet 11 is provided with rows of primary slits 12, secondary slits 14 and tertiary slits 16. As clearly shown in Fig. 1, these slits are in stepped relationship and overlap one another a distance substantially half their length. Between adjacent slits of the rows narrow strips 17 and wide strips 18 are formed. At the center of each slit 12, 14 or 16 and in adjacent strips 17 juxtaposed expansion notches 20 are formed.

As shown clearly in Fig. 2, lacings 23 are extended through the overlapping ends of the slits 12 and 14, 14 and 16, and 16 and 12 so that the narrow strips 17 will be deflected or bent from the sheet 11 in one direction and so that the wide strips 18 will be bent from the sheet 11 in an opposite direction. This is clearly shown in Fig. 4. The strips 17 and 18 cross each other at the center of the slits 12, 14 and 16 where notches 20 are provided. As clearly shown in Fig. 4, the bending of the strips 17 and 18 disaligns the notches 20 to the extent that the side walls thereof are in different planes and will not contact.

An end strip 27 is provided having slots 28 and 29 formed therein, the slots 28 and 29 being relatively offset. As is obvious from Fig. 2, between the ends of the slits 12, 14 or 16 of any row there are formed pairs of strips, a narrow strip and a wide strip. The

end piece 27 is installed on the end of the sheet 11 so that alternate pairs of strips extend through the slots 28 and 29. Other alternate pairs of strips extend below the end piece 27, as shown clearly in Fig. 6.

In securing the wall board of my invention to studs of the wall construction, nails 31 are driven through wide strips 18 and through interlacings 23. Nails 33 are also driven 10 through the end piece 27, these nails passing through certain of the wide strips 18.

After the wall board has been installed in place the plaster is applied on the surface thereof, as indicated at 35 in Fig. 5. As previously mentioned, moisture is absorbed from the plaster by the wall board, thus causing the wall board to expand. The strips 17 and 18 of the sheet 11 expand from the size shown in Figs. 2 and 3 to the size shown in Figs. 5 20 and 7. By bending the strips 17 and 18 out of alignment and by providing expansion notches 20 at the point of intersection of these strips, it is possible for them to expand without interference, thus eliminating a buckling 25 of the wall board. The strips 17 and 18 may expand until the bottoms of the notches 20 engage, as shown in Figs. 5 and 7. When the plaster hardens, the strips 17 and 18 are rigidly locked in the position shown in Fig. 5. 30 By bending the strips 17 and 18 by use of the lacings 23 it is possible to provide key depressions 37 in the surface of the sheet 11. When plaster is applied to the wall board it is forced into these depressions 37 and 35 securely locks the plaster in place to the wall board.

By providing the end piece 27 as shown in Figs. 2 and 6, it is possible to have end protection for the sheet 11 and to reduce the 40 tendency of splitting when the nails 33 are driven therethrough. It is found in practice that without the end piece 27 the sheet 11 would splinter, thus making an insecure attachment. The end piece 27 is of such a 45 character that the pairs of strips 17 and 18 are woven therethrough so as to hold it in place.

The principal feature of my invention is to provide a wall board which will not buckle. 50 This is accomplished by the provision of the notches 20 which as previously mentioned, allow relative expansion between adjacent strips. It is possible to make the wall board from the very cheapest material due to the 55 fact that any buckling from expansion is eliminated. The cheaper woods absorb considerably more moisture than the more expensive woods and therefore have a higher co-efficient of expansion. I have made wall boards similar to the one shown in my drawings, but without the expansion joints. These walls boards I made from the expensive woods which have a low co-efficient of expansion. The cost of these woods is prohibitive to their use in wall board however. 60

With my expansion joint it is possible to make a wall board as shown in the drawings from a cheap and highly expansible material without buckling when the plaster is applied thereto. The use of the interlacings 70 23 in bending the strips 17 and 18 provides novel key depressions which serve to secure the plaster in place.

I claim as my invention:

1. A wall board comprising: a sheet having 75 slits cut therein thus forming strips, there being juxtaposed notches formed in adjacent strips; and lacings extending through said slits for disaligning said juxtaposed notches.

2. A wall board comprising: a sheet having slits cut therein thus forming strips, there being juxtaposed notches formed in adjacent strips; and lacings extending through 80 said slits on both sides of said notches, said lacings bending said strips in a manner to disalign said notches.

3. A wall board comprising: a sheet having overlapping slits cut therein thus forming strips, there being juxtaposed notches formed in adjacent strips; and lacings extending through 85 said slits for disaligning said juxtaposed notches.

4. A wall board comprising: a sheet having overlapping slits cut therein thus forming strips, there being juxtaposed notches formed in adjacent strips; and lacings extending through said slits on both sides of 90 said notches, said lacings bending said strips in a manner to disalign said notches.

5. A wall board comprising: a sheet having rows of primary, secondary and tertiary slits arranged in overlapping relationship, said slits forming pairs of strips between each slit of each row, there being juxtaposed notches formed in adjacent strips; lacings extending through 95 said rows of slits for bending said strips, thus disaligning said juxtaposed notches; and an end piece having slots, said end piece being placed on the end of said sheet so that alternate pairs of strips extend through said slots.

6. A wall board sheet comprising: a sheet of flexible material having overlapping parallel slits cut therein to provide strips and cooperating expansion notches formed in the adjacent strips.

7. A wall board sheet comprising: a sheet of flexible material having overlapping slits cut therein to provide strips, each slit being appreciably enlarged transversely at a point aligned with the ends of the adjacent slits.

8. A wall board sheet comprising: a sheet of flexible material having overlapping slits cut therein to provide strips and cooperating expansion notches formed in the adjacent strips.

9. A wall board sheet comprising: a sheet of flexible material having parallel slits cut therein and disposed in overlapping relation

to an extent of approximately one-half their respective lengths and transversely spaced to provide wide and narrow strips alternating transversely and longitudinally of said sheet, 5 each slit defining one edge of a wide strip and one edge of the longitudinally adjacent narrow strip, the adjacent edge of each strip

being notched to provide an expansion opening at opposite ends of each strip.

In testimony whereof, I have hereunto set 10 my hand at Los Angeles, California, this 3rd day of June, 1925.

EDWARD J. O'BRIEN.
